UNITED STATES PATENT OFFICE.

WILLIAM A. JEX, OF ROCHESTER, NEW YORK.

COMBUSTION-ENGINE.

1,110,390.

Specification of Letters Patent. Patented Sept. 15, 1914.

Application filed June 16, 1913. Serial No. 773,971.

To all whom it may concern:

Be it known that I, WILLIAM A. JEX, a citizen of the United States, residing at No. 88 Adams street, in the city of Rochester, county of Monroe, and State of New York, have invented certain new and useful Improvements in Internal-Combustion Engines, of which the following is a specification.

10 My invention relates to improvements in a rotary valve for internal combustion engines, especially in the means for mounting same and in the provision for the intake of the fuel, and for the exhaust of the burned

15 gases through stationary water cooled diagonal passageways inside the rotary valve and it has for its primary object to provide an improved valve, in which the moving parts for controlling the fluid contents 20 of the explosion space shall be positively acting, perfectly cooled and gas tight, and further to provide a very desirable opening, such as a quick opening, a long dwell and a quick closing of large ports.

25 According to the present invention I provide a cylinder having a closed and an open end with the ports for induction and exhaust and a reciprocating piston operating therein. Mounted on the closed end of the 30 cylinder I provide a valve chamber, containing a stationary passageway cylinder, telescoped by a cylindrical rotating valve which may be in the form of a single rotating cylinder or in the form of an inner and 35 outer cylinder respectively adapted to rotate in opposite directions.

With these ends in view, the invention 40 consists in certain features of novelty in the construction, combination and arrangement of parts hereinafter described, and particularly pointed out in the claims following the description, reference being had to the accompanying drawings, forming a part of this specification, wherein:

45 Figure 1 represents a longitudinal section through the head of one unit of an internal combustion engine fitted with a rotary valve constructed and arranged according to this invention. Fig. 2 represents a longitudinal 50 section at right angles to Fig. 1 through the head of a two cylinder internal combustion engine built up from units such as are shown in Fig. 1 showing the arrangement of

the intake and exhaust passageways through the stationary valve cylinder in the rotary 55 valve. Fig. 3 shows in longitudinal section a modified construction of an internal combustion engine with a valve formed of inner and outer cylinders adapted to rotate in opposite directions, showing the exhaust 60 valve open. Fig. 4 is a similar section showing the position of the inlet ports when the valve is in the position shown in Fig. 3. Fig. 5 represents another modification from that shown in Figs. 3 and 4 showing the 65 arrangement of an inner and outer valve cylinder.

Throughout the drawings like parts are designated by similar reference characters.

Referring to the drawings 2 represents the 70 rotary valve 3 the valve chamber extension and 4 the fixed or stationary valve cylinder. The said extension 3 is preferably cast integral with the working cylinder 1 and its hollow interior forms the valve chamber. 75

The inlet and exhaust ports 5^a, 6^a respectively are formed in the cylinder head and the inlet and exhaust ports 5^b, 6^b respectively are formed in the extension 3 said ports being arranged diagonally opposite each other 80 and in different planes as shown in Fig. 2.

The inlet and exhaust passageways 7, 8 respectively in the stationary valve element 4 are formed to register with the ports 5^a, 6^a in the cylinder head and 5^b, 6^b in the extension 85 aforesaid, between which the ported rotary valve 2 is adapted to be rotated so as to cut off and establish communication at the proper times between the said ports in the cylinder head and the ports in the extension 90 through the passages 7 and 8. The rotary valve is provided with two inlet ports diagonally opposite and two exhaust ports diagonally opposite each other and in different planes each of which controls its own 95 ports in the extension and cylinder head as the valve rotates as in the construction shown in Fig. 2.

As shown in Fig. 2 in which an engine 100 provided with a single rotary valve is illustrated, the said rotary cylindrical valve 2 is elongated and extended beyond the open end of the valve chamber, there terminating in the form of a sprocket wheel 18 whereby the said valve may be rotated from the 105 crankshaft at the proper speed through any

convenient intermediate transmission gear. In either of the two arrangements of valves shown the valve would require to be rotated at half speed of the crankshaft, for an engine working on a four stroke cycle.

Both the stationary valve element 4 and the extension 3 are provided with water jackets 9, 10 respectively as shown, and in the former case said jacket 9 communicates with the ordinary cylinder jacket by the passages 11 and 12. The valve is thus surrounded on all sides by water cooled surfaces. To prevent the escape of the gas longitudinally of the surface of the valve I provide the packing rings 13, inserted between the valve ports substantially as shown in Fig. 2.

In Figs. 3, 4 and 5 I show a modified construction of the rotary valve of my invention. The rotating valve, as shown in the drawings, is here formed of an inner and outer cylinder 14 and 15 respectively adapted to be rotated in opposite directions by means of suitable transmission gearing. The said cylinders 14 and 15 are extended as shown and are provided with toothed sprocket wheels 16 and 17 at their extremities which are rotated from the crankshaft at the proper speed through any convenient intermediate transmission gear. The said cylinders 14 and 15 are provided with two inlet ports diagonally opposite and two exhaust ports diagonally opposite each other in different planes to correspond with the ports in the cylinder head and extension.

It will be obvious that as the cylinders 14 and 15 are rotated in opposite directions they will cut off and establish communication at the proper times between the ports in the cylinder head and in the extension through the passages 7 and 8. By the arrangement of the said pair of valve cylinders rotating in opposite directions I obtain an enlargement of the ports and effect a more rapid opening and closing of said ports.

The operation: At the moment when the ports in the valve are registering with the inlet ports of the cylinder the piston is descending and creating a suction, the charge is then compressed by the next stroke of the piston and ignited at the next stroke. At the moment of ignition the engine shaft has accomplished one complete revolution, while both ports in the cylinder have been closed during the compression and ignition. On the continued rotation of the shaft the exhaust port is opened and the gases escape on the next stroke of the piston, thus completing a cycle of four strokes of the piston for every revolution of the valve.

I do not wish to be understood as limiting myself to the exact details of construction shown and described, as they may be

variously modified within the spirit and intended scope of my invention. For instance two separate valve chambers and valves may be employed one for induction and one for exhaust without affecting the principle of the valve mechanism. Suitably arranged ball bearings may be employed between the valve end and the cylinder extension if found necessary.

As shown in Figs. 2 and 5 the exhaust ports may be united and lead to one conduit, while the induction ports may be similarly united by adding more units.

Having now particularly described and ascertained the nature of my said invention and in what manner the same is to be performed, I declare that what I claim is:

1. In a combustion engine, the combination with a series of cylinders having ports; of a valve casing extending along said series said casing having ports respectively in communication with the ports in the cylinders, through a fixed tubular valve cylinder having diagonal passageways therethrough so located as to connect the ports in the cylinders with the ports in the casing, the entrance and exit to said diagonal passageways being arranged in different planes with packing rings interposed between them to prevent the escape of the fuel longitudinally; the ports of adjacent cylinders being united at the casing; said fixed tubular valve cylinder being chambered to admit a cooling fluid, a rotary valve cylinder interposed between the fixed tubular valve cylinder and the valve casing with ports in its periphery so located as to throw the ports in the cylinders successively into communication with the ports in the valve casing through the diagonal passageways in the fixed valve cylinder.

2. In a combustion engine, the combination with a series of cylinders having inlet and outlet ports; of a valve casing extending along said series and having intake and exhaust ports respectively in communication with the ports in said cylinders through a fixed tubular valve cylinder having diagonal passageways therethrough so located as to connect the inlet ports in the cylinders with the intake ports in the valve casing and the outlet ports in the cylinders with the exhaust ports in the valve casing, the respective ports of adjacent cylinders being united at the valve casing, the entrance and exit to said passageways being arranged in the different planes with packing rings interposed between them to prevent the escape of the fuel longitudinally; said fixed tubular valve cylinder being chambered to admit a cooling fluid, a rotary valve cylinder interposed between the fixed tubular valve cylinder and the valve casing with ports in its periphery so located as to throw the inlet

and outlet ports in the cylinders successively into communication with the intake and exhaust ports in the valve casing respectively through the diagonal passageways in 5 the fixed tubular valve cylinder, substantially as described.

In witness whereof I have hereto set my

hand, in the presence of two subscribing witnesses, this 12th day of June 1913.

WM. A. JEX.
